UNITED STATES PATENT OFFICE.

FRED HIRSH, OF NEW YORK, N. Y.

HOSE-SUPPORTER.

No. 852,954.

Specification of Letters Patent.

Patented May 7, 1907.

Application filed November 1, 1906. Serial No. 341,531.

To all whom it may concern:

Be it known that I, FRED HIRSH, a citizen of the United States, residing in the city of New York, in the county and State of New York, have invented certain new and useful 5 Improvements in Hose-Supporters, of which the following is a specification.

The object of my invention is to provide a hose supporter which shall be simple, cheap, comfortable and efficient; and this I attain by means of certain features of construction, combination and arrangement of parts, as hereinafter described, and as illustrated in the accompanying drawing, in which—

15 Figure 1. is a perspective view of my improved hose supporter, showing the way in which it is intended to be used; and Fig. 2. is a side view of one end thereof.

Similar reference characters indicate corresponding parts in the two figures.

The numeral 1 represents a strap or band of any suitable material, as elastic webbing, which is of a length sufficient to allow it to be passed around the leg and crossed as shown, and which constitutes the main portion 25 of the hose supporter. At or near one end of this strap I form a loop 2, preferably by means of a strip 3 of the same material sewed at each end to the outer side of the strap, as shown, through which the other end 30 of the strap may be passed to fix and retain the crossing of the two ends. Preferably, also, I form a second loop 4 above the first loop, by extending the upper end of the strip 3 as at 5 and sewing it to the strap as shown, or in any other suitable manner; the second or upper loop serving as a means of adjustment, since by passing the other end of the strap through this loop the crossing is raised

higher up on the leg and the supporter is in effect thereby shortened as indicated by dotted lines. To each end of the strap 1, I attach a suitable fastening device by which the supporter may be secured to the top of the hose; preferably using for this purpose a metal clasp 6, consisting of two hinged members co-operating when swung together to lock and secure the hose between them, which is attached to the band in such a way that the end of the band will form a covering 50 for the outer surface of the back clasp member and so keep the metal clasp from coming in contact with the leg or undergarment of the wearer, all as shown, described and claimed by me in an application filed November 6, 1905, Serial No. 285,970.

The manner of using my new hose supporter and its advantages are obvious and need not be recited.

What I claim as new, and desire to secure by Letters Patent, is—

A hose supporter consisting of a strap comprising a single piece of elastic webbing adapted to pass around the leg and cross, one or more permanent loops formed on the strap near one end by attaching thereto a separate piece of elastic webbing through which to pass the other end of the strap to fix or adjust the crossing, and a fastening device so attached to each end of the strap that the strap will form a covering for the back of the fastening device.

In testimony whereof I have signed my name in the presence of two witnesses.

FRED HIRSH.
